JACQUES MAYER AND CARL MUEHLEISEN, OF BERLIN, GERMANY, ASSIGNEES TO
MERGENTHALER LINOTYPE COMPANY, A CORPORATION OF NEW YORK.

MATRIX FOR LINOTYPE-MACHINES.

1,105,204.

Specification of Letters Patent. Patented July 28, 1914.

Application filed December 13, 1905. Serial No. 291,555.

To all whom it may concern:

Be it known that we, JACQUES MAYER and CARL MUEHLEISEN, both citizens of the United States of America, and residing at Berlin, in the Empire of Germany, have invented a new and useful Matrix for Linotype Machines, of which the following is a specification.

Our invention relates to the circulating matrices which are composed temporarily in line for presentation to a slotted mold to form type characters in relief on slugs cast in such mold.

The object of the invention is primarily to greatly prolong the life of the matrices at a slight increase in the cost of manufacture.

To this end it consists in providing each matrix with two identical characters and with the same character in a different face or style less frequently used, so that the use and wear of a matrix may be distributed between the duplicate characters and its life thus prolonged until the third and less frequently used character has become inoperative from use.

Matrices for linotype machines have heretofore been provided with the same character in variant forms, so that either character could be presented to the mold at will. Certain faces or forms are used with much greater frequency than others; for example, ordinary reading characters are used more frequently than italics or black faces. When, therefore, a matrix has a single character of each form, it is found that the character most frequently used becomes worn and inoperative and the matrix therefore useless, while the second character is still in good condition. In consequence of this fact there is a large loss to the printer due to the rejection of matrices which are inoperative condition as to one set of characters. By providing such matrices with two of the frequently used characters instead of one, we are enabled to distribute the work between the two characters and thus prolong the life of the matrix. The same extension of life is also secured when the matrix is provided with two or three characters identical in every respect, as they may be presented successively to the mold and the wear distributed between them, the type faces produced being the same regard-

less of which character on the matrix is presented to the mold.

Referring to the drawings: Figure 1 is an elevation of a matrix with three intaglio letters, of which two are identical. Fig. 2 is a side view of the same. Fig. 3 is a side view of a modification of the same. Fig. 4 illustrates the manner in which the matrix shown at Figs. 2 and 3 is so applied to a mold that its lower intaglio letter is opposed to the single cell or slot; and Fig. 5 illustrates the manner in which the same matrix is so applied to the said mold that its middle intaglio letter is opposite to the single cell or slot.

The matrix *b* shown in Figs. 2 and 3 is provided with three superposed intaglio letters 1, 1 and 2 of the same font. The two letters 1, 1 above and below are exactly alike, while the third letter 2 in the middle is of a distinct kind, or say thicker or bolder than the former. Then the one of the two intaglio letters 1, 1 is used until it is worn out, after which the other one is engaged for use in casting types. It is assumed that either of the two letters 1, 1 is used more frequently than the third letter 2, so that the latter may be worn out about at the same time as the other letters. We do not, however, limit ourselves in this respect. With some of the matrices the third letter 2 may represent a different character, which is seldom used, as is for example shown at Fig. 3. Figs. 4 and 5 illustrate the manner in which the matrix *b* may be applied to the mold of an ordinary linotype machine. The mold *c* is provided with two grooves *e* and *e'* parallel to the mouth of the single cell or slot *d*, and the lugs *b'* of the matrices *b* are arranged to engage in either of the two grooves *e* and *e'*. If so preferred, the matrix may be provided with more than three intaglio letters representing the same character of the same font. One of these intaglio letters may be of a distinct kind, while the others are of an ordinary kind. Preferably the intaglio letter of the distinct kind is placed in the middle between the other letters, or nearly so.

What is claimed and desired to be secured by Letters Patent is,

A linotype matrix having an edge of uniform thickness provided with plural, identical, separately usable character impressions therein and with an additional

character impression therein, of a less frequently used kind, whereby the life of the matrix may be prolonged to correspond with the life of the less frequently used character, the said matrix being provided with the usual distributing teeth, and with means co-operating with the mold for locating the several character impressions respectively in position for casting therefrom.

In testimony whereof we have signed our names to this specification in the presence of two subscribing witnesses.

JACQUES MAYER.
CARL MUEHLEISEN.
